CLAIM

(56) **References Cited**

The ornamental design for a reciprocating coin moving mechanism for transparent coin sorter, as shown and described.

DESCRIPTION

FIG. 1 is a perspective view of a reciprocating coin moving mechanism for transparent coin sorter showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof; and,

FIG. 7 is a front elevational view thereof.

The coin sorting housing outlined in broken lines in FIG. 1 forms no part of the claimed design.
